UNITED STATES PATENT OFFICE.

CARL A. W. WESTHOLM, OF CHICAGO, ILLINOIS.

COMBINED ENVELOP AND LETTER-SHEET.

No. 873,691.

Specification of Letters Patent.

Patented Dec. 10, 1907.

Application filed March 21, 1907. Serial No. 363,629.

To all whom it may concern:

Be it known that I, CARL A. W. WESTHOLM, a citizen of the United States, residing at Chicago, in the county of Cook and State 5 of Illinois, have invented new and useful Improvements in Combined Envelops and Letter-Sheets, of which the following is a specification.

The invention relates to a combined envelop and letter sheet, in which the blank is 10 of peculiar formation to permit it after being written upon to be folded to present an envelop of ordinary form.

The main object of the present invention 15 is the provision of a combined envelop and letter sheet in which the stamp used for mailing purposes is utilized as the sealing element.

The invention will be described in the following specification, reference being had particularly to the accompanying drawings, in which:—

Figure 1 is a view showing the complete invention folded and ready for mailing, Fig. 25 2 is a similar view showing the blank in folded form previous to the final sealing, Fig. 3 is a view of the rear face of the blank forming the combined letter sheet and envelop.

Referring to the drawings, my improved 30 combined letter blank and envelop comprises a blank 1 of approximately rectangular outline and, of course, of any desired dimensions.

The blank is marked or otherwise indicated for folding along the longitudinal median line 2 to provide sheets 3 and 4, and the blank is further indicated for folding along transverse lines 5 and 6, which are equally spaced from each other and from the proximate edges of the blank. The blank as thus indicated for folding provides six equal sections, and when folded presents an envelop having a length and width equal to one of the sections.

45 Immediately adjacent the juncture of the lower edge and free side edge of one of the sections the blank is formed with a projecting tab or tongue 7, the lower edge 8 of which is arranged on a plane above the relatively 50 lower edge of the blank, while the upper edge 9 extends from the free end of the tab in par-

allel relation to the lower edge for a short distance and then curves upwardly at 10 into coincidence with the proximate side edge of the blank. The section of the blank immediately above the section form of the tab is provided adjacent its free side edge and also adjacent the relatively upper edge of the section with a slit 11, which slit is spaced from the free edge of the section a distance less than the length of the tab 7, and in length is greater than the width of the tab adjacent its free end.

With the blank thus constructed the face surface thereof is inscribed as desired by the 65 sender, after which the blank is folded along the median line 2 to dispose the inscribed surfaces of the sections 3 and 4 in contact. After folding along the line 2 the section above the line 5 is folded down upon the next 70 lowermost section, and the section below line 6 is folded upward in rear of the section just described. In this position the section of the blank carrying the slit 11 appears as the face section of the folded article, and while 75 the section bearing the tab 7 appears as the rear section.

In sealing the envelop the tab 7 is folded over onto the section bearing the slit 11, or the face section with its free end inserted in 80 the slit, after which a postage stamp, as 12, is applied to overlie the slit and bear upon the face section and upon the tab. The cut out portion 8 of the tab forms a very material part of the invention in this use, as there- 85 by a portion of the face section of the envelop is exposed above the tab to which exposed portion the stamp is secured. The stamp thus secures the sealing tab in place and effectually seals the structure against unauthorized opening. Owing to the cutaway portion 8 of the tab the stamp is fixed to the face section of the envelop on both sides of the slit, and also to the tab, thereby more firmly sealing the parts in place than would 90 be otherwise possible.

Having thus described the invention what is claimed as new, is:—

A combined envelop and letter sheet comprising a blank of rectangular outline ar- 100 ranged for folding to provide a plurality of sections, one of the sections being formed

with a tab and the adjacent section being formed with a slit to receive the end of the tab, said tab being cutaway on its lower edge to expose a portion of the section bearing the 5 slit, said combined envelop and letter sheet being adapted to receive a sealing strip to be secured to the section formed with a slit and to the tab, whereby the sealing strip may

engage the section carrying the slit on both sides of the latter and also engage the tab. 10

In testimony whereof, I affix my signature in presence of two witnesses.

CARL A. W. WESTHOLM.
